UNITED STATES PATENT OFFICE.

JACOB RUBINOFF, OF NEW YORK, N. Y.

DESIGN FOR A COMBINATION SIGNAL AND LICENSE PLATE HOLDER.

Application filed July 25, 1923. Serial No. 6,855. Term of patent 3½ years.

To all whom it may concern:

Be it known that I, JACOB RUBINOFF, a citizen of the Republic of Russia, residing at New York, in the county of New York and State of New York, have invented a new, original, and ornamental Design for a Combination Signal and License Plate Holder, of which the following is a specification, reference being had to the accompanying drawing, forming part thereof.

The figure is a perspective view of a combination signal and license plate holder, showing my new design.

I claim:

The ornamental design for a combination signal and license plate holder substantially as shown.

JACOB RUBINOFF.
